UNITED STATES PATENT OFFICE.

SAMUEL C. SALMON, OF MANHATTAN, KANSAS.

DRILL.

1,330,451.

Specification of Letters Patent. Patented Feb. 10, 1920.

Application filed July 12, 1918. Serial No. 244,520.

To all whom it may concern:

Be it known that I, SAMUEL C. SALMON, a citizen of the United States, residing at Manhattan, in the county of Riley and State of Kansas, have invented a certain new and useful Improvement in Drills, of which the following is a specification.

My invention relates to improvements in drills. It relates particularly to grain drills of the type provided with disks arranged in pairs adapted to make deep furrows in which the seeds are planted, the furrows being separated by prominent ridges.

One of the objects of my invention is the provision of a drill of the kind described which will be of light draft and which will eliminate excessive lateral swinging of the gangs of disks.

Another object of my invention is the provision of novel and efficient means for vertically adjusting the disks.

Still another object of my invention is the provision of novel means by which the drill is adapted to be adjusted to different positions to accommodate it to draft horses of different height.

The novel features of my invention are hereinafter fully described and claimed.

In the accompanying drawings, which illustrate the preferred embodiment of my invention,

Figure 1 is a view partly in vertical section and partly broken away, of my improved drill.

Fig. 2 is a top view of one of the draw bars and disks carried thereby.

Fig. 3 is a side view of the one of the draw bars shown partly broken away, and some of the parts connected therewith.

Fig. 4 is a plan view, partly broken away, of my improved drill.

Fig. 5 is a rear view of two of the disks, shown in operative position in the soil, and a part of one of the seed dropping tubes.

Fig. 6 designates a horizontal frame pivoted on a horizontal axis on an axle 2 on which are mounted the usual carrying wheels 3.

Pivoted at their forward ends to the front part of the frame 1 are a plurality of draw bars, on each of which are carried two concavo-convex disks 5 and 6 of the usual type. The disks of each pair are faced in opposite directions and are disposed in substantial longitudinal alignment, one in advance of the other, with the forward disk in all operative positions higher than the rear disk.

For supporting the front disk 5 of each pair, I provide a vertical plate 7 having a pair of vertical slots 8 through which extend two bolts 9 respectively, which extend 60 through the adjacent draw bar 4 and which are provided with nuts 10. A stud 11 fastened to the plate 7 serves as a support for the rotary disk 5.

The rotary disk 6 is mounted on a stud 65 12, which is supported on a vertical plate 13, which is provided with two vertical slots 14 through which extend respectively two bolts 15, which extend through the adjacent draw bar 4 and are respectively provided 70 with nuts 16.

The manner of securing the plates 9 and 13 to the draw bar permits of each of the disks of a pair being vertically adjustable 75 on the draw bar independently of the other disk.

The plate 13 is provided with a laterally and rearwardly extending arm 17, Fig. 3, through which extends a seed dropping tube 18, which has its lower end disposed so as 80 to drop the seed in the bottom of the furrow 19, shown in Figs. 1 and 5. For covering the seed which has been deposited in the furrows, each tube 18 has attached to it the forward end of a chain 20, Fig. 1, arranged to drag along in the furrow.

The seed tubes 18 are connected at their upper ends in the usual manner to a transverse seed box 21 of the usual type.

For swinging the draw bars 4 on the 90 frame 1, each draw-bar has pivoted to it indeterminate of the disks 5 and 6, the lower end of a bar 22, the upper end of which is provided with a longitudinal slot 23 through which extends a pin 24, Fig. 1, carried at 95 one end of a crank arm 25, which is secured rigidly to a transverse horizontal rock shaft 26 mounted in suitable bearings 27 secured to the frame 1 and having secured to it a lever 28, which is adapted to be locked to an 100 arcuate plate 29, having peripheral teeth 30 adapted to be engaged in the usual manner by a sliding bolt 31 mounted on the lever 28 and connected by a link 32 with a bell crank lever 33 which is pivoted on the lever 105 28 and which has connected to it a link 34, which is pivotally connected to a bell crank lever 35 pivoted on the lever 28 adjacent to the handle at the upper end thereof.

A coil spring 36 encircles each bar 22 110 and has its lower end bearing against the adjacent draw bar 4, and has its upper end

bearing against the adjacent crank arm 25. This spring permits the draw bar to swing upwardly, when the disks strike a rock or other hard substance.

5. By swinging the lever 28, the draw bars 4 operated thereby may be vertically swung to any desired position.

In Fig. 4 of the drawings there are shown two sets of draw bars, three in each set, the 10 connecting bars 22 of one set being pivoted respectively to three crank arms 25 of a rock shaft 26 having secured to it an operating lever 28. A similar rock shaft 26 having three crank arms 25 is disposed in 15 longitudinal alinement with the other rock shaft. The last named three crank arms 25 are pivoted respectively to three bars 22 which are respectively pivoted to the draw bars 4 of the other set. The front disks 20 of the right hand set have their concave sides facing to the right, and the front disks 5 of the other set have their concave sides facing to the left. The rear disk of each 25 pair faces with its concave side in a direction opposite to the front disk of the pair. By this arrangement the lateral pressure is equalized.

Preferably the draw bars are spaced apart so that the furrows made by the disks 5 30 and 6 will be the same distances apart.

Each of the rock shafts 26 is provided with an operating lever 28 having the means already described for being releasably locked to a peripherally notched plate 29.

35. It is sometimes desirable to vertically adjust the frame 1 by swinging it on its axis, for the purpose of lowering the front disks 5, or raising them, without correspondingly moving the rear disks in a like direction to 40 the same extent. This may be accomplished in different ways. In the drawings, I have shown a means for vertically swinging the frame 1 comprising the following described parts:—

45. 36 designates a forwardly extending tongue connected by a horizontal transverse bolt 37 with two links 38 which are pivoted by a horizontal transverse bolt 39 mounted in the arms of a U shaped bracket 50 40, which is secured to the top and forward part of the frame 1. Secured to the rear end of the tongue 36 is a plate 41 having an arcuate notched upper edge adapted to be releasably engaged by a sliding bolt 42, 55 which is mounted on a lever 43, which is pivoted by a horizontal transverse bolt 44 to the plate 41. The bolt 42 has pivoted to it a link 45 which is pivoted to a bell crank hand lever 46, which is pivoted to 60 the lever 43. The lower end of the lever 43 is provided with an arm 47, which is pivoted to a link 48, which is pivoted by a transverse horizontal pin 49 to a bearing 50, which is fastened to a transverse bar 51 65 of the frame 1.

By swinging the upper end of the lever 43 rearwardly, the arm 47 and the link 48 will straighten out, thus lifting the rear end of the tongue 36, and, through the intermediacy of the links 38, bolts 37 and 39 and bracket 40, lifting the forward end of the frame 1, thereby lifting the forward ends of the draw bars 4. The front disks 5 will thus be lifted to a greater extent than the rear disks 6. Upon swinging the lever 43 forwardly, the arm 47 and link 48 will draw the rear end of the tongue 36 downwardly, thus swinging downwardly the forward end of the frame 1 and the forward ends of the draw bars 4, thereby carrying 80 downwardly the front disks 5.

By swinging the levers 28, the rear ends of the draw bars 4 may be moved vertically, thereby moving the rear disks 6 vertically to a greater extent than the disks 5.

From the foregoing it will be understood that by properly operating the levers 28 and 43, the front and rear disks may be adjusted relatively to any desired positions within the limits of their movements.

As the front disks 5 are, in the operative positions below the surface of the ground, always higher than the rear disks, and as the disks of each pair are in substantial longitudinal alinement with each other, the 95 rear disks will, by cutting fresh earth at a depth lower than that reached by the front disks, do the same work, or substantially the same work as the front disks which preliminarily break the ground. It is desirable, 100 however, to be able to vary the depth that the front disks shall enter the ground without substantially changing the depth of travel of the rear disks. This may be accomplished, by operating the levers 28 and 105 43 in the manner already described.

By having the tongue connected to the frame pivotally and with the lever 43 and link 48, the height of the forward end of the tongue can be varied to suit the height 110 of the horses hitched thereto, without changing the depth of travel of the disks 5 and 6.

Thus by holding the front of the frame 1 at the desired height, with the disks set, 115 as desired, the front end of the tongue 36 can be lowered, for attachment to a smaller team of horses, by swinging the lever 43 rearwardly at its upper end. Or the front end of the tongue may be lifted, for attachment to a team of greater height, by swinging the upper end of the lever 43 forwardly.

As shown in the drawing, the front and rear disks of each pair are disposed reversely to each other but with their cutting 125 edges at substantially the same angle to the line of draft.

This arrangement of the disks together with the disposition of the front disks higher than the rear disks, in the operative 130

positions, makes the draft light and equalizes the lateral pressure. By having the front disks adjustable vertically to a greater extent, if desired, than the rear disks, the drill is adapted for varying conditions of the ground and character of the soil, and for different kinds of seeds, which may require different manipulation of the soil.

With my improved drill, the seed is planted at the bottom of a furrow. The prominent ridges between the furrows afford ample protection to the seed in many ways. They insure an abundance of moisture, whether due to snow or rain, being retained at the bottom of the furrows; and, where the soil is light and the winds high, the dirt is not blown off from the seeds. With the seeds so planted, they are not injuriously affected by the action of frost in the ground.

I do not limit my invention to the structure shown and described, as modifications, within the scope of the appended claims, may be made without departing from the spirit of my invention.

What I claim is:—

1. In a drill, a pair of oppositely facing concavo-convex disks, and vertically adjustable means for supporting the disks in substantial longitudinal alinement one in advance of the other with the front disk in all operative positions higher than the rear disk, the disks being arranged to throw the dirt at opposite sides of a furrow made by them.

2. In a drill, a pair of oppositely facing concavo-convex disks, means for supporting the disks in substantial longitudinal alinement one in advance of the other with the front disk in all operative positions higher than the rear disk, the disks being arranged to throw the dirt at opposite sides of a furrow made by them, and means for adjusting the supporting means so that the disks will

be adjusted vertically one to a greater extent than the other.

3. In a drill, a pair of oppositely facing concavo-convex disks, means for supporting the disks in substantial longitudinal alinement one in advance of the other with the front disk in all operative positions higher than the rear disk, the disks being arranged to throw the dirt at opposite sides of a furrow made by them, and means for adjusting the supporting means so that the disks will be vertically adjusted the front disk to a greater extent than the rear disk.

4. In a drill, a pair of oppositely facing concavo-convex disks, means for supporting the disks in substantial longitudinal alinement one in advance of the other with the front disk in all operative positions higher than the rear disk, the disks being arranged to throw the dirt at opposite sides of a furrow made by them, and means for adjusting the supporting means so that the disks will be vertically adjusted and providing for the adjustment of either disk to a greater extent than the other.

5. In a drill, two pairs of concavo-convex disks, the disks of each pair being oppositely facing and arranged to throw the dirt at opposite sides of a furrow made by them, means for supporting each pair of disks with the disks of each pair disposed in substantial longitudinal alinement, one in advance of the other with the front disk in all operative positions being higher than the rear disk, means for adjusting the supporting means so that the disks of each pair will be adjusted vertically, one to a greater extent than the other, the two pairs of disks being spaced apart so as to leave respectively two furrows.

In testimony whereof I have signed my name to this specification.

SAMUEL C. SALMON.
